WILLIAM COYNE, OF KEWANEE, ILLINOIS, ASSIGNOR OF ONE-HALF TO DE CLARK BROTHERS, OF KEWANEE, ILLINOIS, A COPARTNERSHIP.

PUMP.

1,081,020.

Specification of Letters Patent.

Patented Dec. 9, 1913.

Application filed April 8, 1912. Serial No. 689,239.

To all whom it may concern:

Be it known that I, WILLIAM COYNE, a citizen of the United States, and a resident of the city of Kewanee, county of Henry, 5 and State of Illinois, have invented certain new and useful Improvements in Pumps, of which the following is a specification.

My invention relates to improvements in pumps, and has for its object the provision 10 of a pump of simple construction and efficient in operation.

The invention consists in the combinations and arrangements of parts hereinafter described and claimed.

15 The invention will be best understood by reference to the accompanying drawings forming a part of this specification, and in which—

Figure 1 is a vertical longitudinal section of a pump embodying my invention, parts being shown in elevation, Fig. 2, a side elevation of the pump with parts shown in section, Fig. 3, a section taken on line $x-x$ of Fig. 2, Fig. 4, a bottom plan view 25 of a casting employed in the pump, and Fig. 5, a bottom plan view of another casting employed in the pump.

The preferred form of construction, as illustrated in the drawings, comprises 30 axially alining cylinders 1 and 2 consisting, respectively, of pipe sections 3 and 4, as indicated. The adjacent ends of cylinders 1 and 2 are formed by castings 5 and 6 seated on the ends of pipe sections 3 and 4 and 35 separated by another pipe section 7 arranged between them and seated thereon. The lower end of cylinder 2 is formed by a casting 8 seated on the lower end of pipe section 4 and the upper end of cylinder 1 is formed by a casting 9 seated on the upper end of pipe section 3. Said parts are 40 firmly bound together by means of tie rods 10 arranged as shown and having nuts 11 on their ends and bearing against the outer 45 sides of castings 8 and 9. Castings 5 and 6 are provided with ports 12 and 13 leading into the ends of the corresponding cylinders 1 and 2, respectively. A downwardly extending intake pipe 14 and an upwardly 50 extending discharge pipe 15 are connected with each of the ports 12 and 13, as shown, and each of said pipes is provided with an upwardly opening check valve 16. Intake pipes 14 are connected at their bottoms with 55 a common intake pipe 17, and discharge

pipes 15 are extended upwardly where they may be provided with any suitable means for utilizing water discharged therefrom. Alternately operating pistons 18 and 19 are arranged in cylinders 1 and 2 and are connected together by means of a common piston rod 20. Piston rod 20 passes through castings 5 and 6 where it is provided with suitable packings and a spring 21 is interposed between said packings in order to 60 keep them tight. By this arrangement it will be observed that upon reciprocation of pistons 18 and 19, water, in communication with pipe 17, will be drawn upwardly into cylinders 1 and 2 alternately and alternately 65 expelled therefrom through discharge pipes 15, check valves 16 opening and closing to cause such action, as will be readily understood by those skilled in the art.

Casting 8 is provided with a port 22 communicating with the lower end of cylinder 2 and an air pipe 23 leads from port 22 to a port 24 in the bottom of valve casing 25, as shown. Casting 9 is provided with a port 26 communicating with the upper end of 70 cylinder 1 and connected by means of a pipe 27 with a port 28 also located in the bottom of valve casing 25. An exhaust port 29 is arranged in the bottom of valve casing 25 between ports 24 and 28, as shown, and a 75 slide valve 30 having a recess 31 in its bottom adapted to place either of the ports 24 or 28 in communication with exhaust port 29, is seated upon the bottom of valve casing 25. Alining valve cylinders 32 and 33 are 80 arranged in valve casing 25 above valve 30 and valve piston heads 34 and 35 are arranged to reciprocate in cylinders 32 and 33, as shown. Valve heads 34 and 35 are connected by a rod 36 which in turn is connected with valve 30 by means of a pin 37. A supply port 38 leads into the top of valve casing 25 between piston heads 34 and 35 and a supply pipe 39 connects with port 38. 85 By this arrangement it will be observed that upon supplying compressed air through pipe 39 and upon properly operating piston valve heads 34 and 35, valve 30 will be caused to operate to admit compressed air to the outer ends of cylinders 1 and 2 alternately and to exhaust the air from said cylinders alternately, to cause reciprocations 90 of the pistons in said cylinders. The arrangement is such that valve heads 34 and 35 fit snugly against the ends of cylinders 95 100 105 110

32 and 33 at the end of each stroke, and in order to give free access of the air to said cylinders and provide sufficient effective piston surface, the valve heads 34 and 35 are 5 provided with recesses 34' and 35' in their ends.

A branch pipe 40 leads from supply pipe 39 and connects with valve casing 41 so as to supply compressed air to the interior 10 thereof. A port 42 is arranged in the side of valve casing 41 and is connected by means of a pipe 43 with a port 44 communicating with the end of valve cylinder 32. Another port 45 is arranged in the side of 15 valve casing 41 and is connected by means of a pipe 46 with a port 47 communicating with the end of valve cylinder 33. An exhaust port 48 is arranged between ports 42 and 45 and is provided with a suitable 20 exhaust pipe 49. A slide valve 50 which is similar in all respects to slide valve 30, is seated upon the side of valve casing 41 and serves, upon reciprocation, to supply compressed air to cylinders 32 and 33 alternately and to exhaust air from said cylinders alternately, to cause reciprocation of valve heads 34 and 35 and consequently reciprocation of valve 30. A block 51 is 25 slidably mounted upon a rod 52 which extends upwardly from piston 18 and is connected thereto to reciprocate therewith. Stops 53 and 54 are arranged on rod 52 above and below block 51 and are so positioned as to cause reciprocation of block 51 at the end 30 of each stroke of the pistons 18 and 19. Block 51 is connected with valve 50, as indicated, so that reciprocations of said block cause corresponding reciprocations of said valve. A guard tube 55 is arranged over 35 the upper end of rod 52 and is adapted to protect said rod and permit reciprocations thereof. By this arrangement it will be observed that at the end of each stroke of pistons 18 and 19 the valve 50 will be automatically shifted to operate valve heads 34 and 35 to exhaust the previously operative cylinder 1 or 2 and to supply compressed air to the other of said cylinders to cause continuous reciprocations of said 40 cylinders as long as discharge from pipes 15 is permitted.

In use, the pump is arranged in the bottom of a well with the end of pipe 17 submerged and pipes 15 connected with the 45 water system which it is desired to supply with water, and compressed air is constantly

supplied through pipe 39. In case discharge of water is permitted from pipes 15, pistons 18 and 19 will be continuously reciprocated to continue such discharge 60 from said pipes as explained above. When the discharge from pipes 15 is discontinued, the water in said pipes and in any system with which they connect, being incompressible, will stop further action of pistons 18 65 and 19, but immediately upon further withdrawal of water from pipes 15, pistons 18 and 19 re-commence their operations. It will be observed that valve heads 34 and 35 are positively and instantly operated by 70 means of the pressure supplied to the pump and thus the action of the pump is rendered entirely automatic and controlled by the withdrawal of water from the discharge pipes, and all danger of stopping of the 75 pump is avoided.

While I have illustrated and described the preferred form of construction for carrying my invention into effect, this is capable of variation and modification without departing from the spirit of the invention. I, therefore, do not wish to be limited to the exact details of construction set forth, but desire to avail myself of such variations and modifications as come within the scope of the 85 appended claim.

Having described my invention, what I claim as new and desire to secure by Letters Patent, is:

In a device of the class described, two 90 aligned pumping cylinders each having a port in the outer end thereof, pistons in said cylinders, a source of compressed air supply, a piston valve arranged to control the admission and exhaust of said compressed 95 air to and from said ports, a second valve arranged to control said piston valve, said second valve operating in alignment with said pumping cylinders, a block connected with said second valve, a rod connected to 100 said pistons and slidably extending through said block, and stops on said rod adapted to alternately engage said block for operating said second named valve, substantially as described.

In testimony whereof I have signed my name to this specification in the presence of two subscribing witnesses.

WILLIAM COYNE.
